(57) **CLAIM**

The ornamental design for a fork arch as shown and described.

DESCRIPTION

FIG. 1 is a rear perspective view of a fork arch showing our new design;

FIG. 2 is a left side elevation view thereof;

FIG. 3 is a right side elevation view thereof;

FIG. 4 is a back elevation view thereof;

FIG. 5 is a front elevation view thereof;

FIG. 6 is a top plan view thereof;

FIG. 7 is a bottom plan view thereof;

FIG. 8 is a front perspective view thereof;

FIG. 9 is a rear perspective view of a fork arch showing our new design, in accordance with a second embodiment;

FIG. 10 is a left side elevation view thereof;

FIG. 11 is a right side elevation view thereof;

FIG. 12 is a back elevation view thereof;

FIG. 13 is a front elevation view thereof;

FIG. 14 is a top plan view thereof;

FIG. 15 is a bottom plan view thereof; and,

FIG. 16 is a front perspective view thereof.

The broken lines in the drawings illustrate portions of the fork arch that form no part of the claimed design.
